UNITED STATES PATENT OFFICE.

FREDERICK R. PARKER, OF CHICAGO, ILLINOIS.

TELEPHONE SYSTEM.

1,026,328.

Specification of Letters Patent.

Patented May 14, 1912.

Application filed November 23, 1904, Serial No. 234,039. Renewed August 23, 1911. Serial No. 645,630.

To all whom it may concern:

Be it known that I, FREDERICK R. PARKER, a citizen of the United States of America, residing at Chicago, in the county of Cook and State of Illinois, have invented a new and useful Telephone System, of which the following is a specification, reference being had to the accompanying drawings, illustrating same.

10 My invention relates to electrical transmitting systems and in particular to telephone systems.

The principal objects of my invention are to provide improved means for operating 15 and controlling the subscriber's or line-signal indicators or annunciators in such a system; to provide improved means for operating and controlling the supervisory or disconnect indicators or annunciators in such a 20 system; to provide improved arrangements of the parts, devices and circuit connections, in such a system; and to provide a telephone system which may be efficiently and effectively operated and utilized without the 25 employment of relays.

Other objects will be apparent from the following specification.

In telephone systems, especially of the central energy or common battery type, it is 30 generally the practice to employ relays to control the circuits of the signaling devices of the system, that is, the line signaling devices and supervisory signaling devices. In my present invention I preferably do away 35 with all of these relays and arrange the circuits of the system so that the line signaling devices and supervisory signaling devices are directly shunted to render them inoperative, when it is desired to extinguish 40 their signals to keep them from displaying signals. I preferably shunt the line signaling device of a line by a resistance or impedance associated with the plug-cord circuit, when connection is made with this 45 line, and preferably shunt the supervisory signaling device which is now connected with the line, by the circuit of the line when same is closed. I preferably employ high-resistance line and supervisory signaling 50 devices, or high-resistances in series therewith, to make the shunt circuits more effective; and it is upon the proper proportioning of all of the resistances of the system that its successful operation depends.

55 I will more particularly describe my invention by reference to the accompanying

drawings illustrating suitable means for accomplishing the desired results, in which,—

Figure 1 is a diagram showing two subscribers' lines and the central station signaling and connecting apparatus; and Fig. 2 is a diagram of a cord circuit showing the windings of a repeating coil in series with the respective supervisory signals and the main strands of the respective connecting 65 cords.

Like characters refer to like parts throughout the drawings.

The line of subscriber A extends in two limbs *a* and *b* from a substation to a central station. Limb *a* is connected to connection terminals *c c* of the several spring jacks *D D* of the multiple switchboard, and through conductor *e*, and winding *h* of impedance coil *I*, to pole *m* of battery *Q*; and limb *b* is connected to terminals *d d* of the several spring jacks *D D*, and through conductor *f*, line-signal lamp *g*, and winding *i* of impedance coil *I*, to pole *n* of battery *Q*.

At the subscriber's station A, the line conductors *a* and *b* are preferably normally disconnected from each other, but are adapted to be conductively connected together through the subscriber's telephone when the receiver is taken from the switch-hook, in a 85 manner well understood.

The line of subscriber B is similar to that of subscriber A, except that in line B I preferably show lamp *g* connected direct to pole *n* of battery *Q*, through conductor *j*. When 90 lamp *g* is connected direct from a limb of the line to the central source of electricity, as in line B, it is preferably of a high resistance.

In the plug-cord connecting circuit, tip 95 strand *a₂* of answering plug *E* is normally connected through condenser *e₂*, contact *n₂*, and spring *m₂* of ringing key *H*, to tip strand *u₂* of calling plug *F*. Sleeve strand *b₂* of answering plug *E* is normally connected through condenser *f₂*, spring *p₂* of listening key *G*, contact *o₂*, contact *r₂*, and spring *s₂* of ringing key *H*, to sleeve strand *v₂* of calling plug *F*. Spring *j₂* of listening key *G* is connected with contact *n₂* and condenser *e₂*. Supervisory-signal lamp *c₂* is connected from tip strand *a₂* of answering plug *E*, preferably through winding *d₂* of impedance coil *N*, to sleeve strand *b₂* of said plug *E*. Supervisory lamp *g₂* is connected from spring *p₂* to contact *k₂* which normally engages spring *j₂*. Sleeve strand *b₂* of an-

- swering plug E is connected through impedance coil O and conductor y_2 , to pole n of battery Q, and spring p_2 is connected through conductor w_2 , impedance coil P, and conductors z_2 and j , to pole u of battery Q.
- 5 It is immaterial which is the positive or negative pole of battery Q. The operator's telephone is to be connected from contact i_2 to contact q_2 , in a manner well understood.
- 10 A ringing generator is to be connected from contact l_2 to contact t_2 , also in a manner well understood.

When the listening key G is depressed, springs j_2 and p_2 are disengaged from contacts k_2 and o_2 , respectively, and engaged with contacts i_2 and q_2 , respectively. When the ringing key H is depressed, springs m_2 and s_2 are disengaged from contacts n_2 and r_2 , respectively, and engaged with contacts l_2 and t_2 , respectively.

- 20 The operation of the system is as follows: If subscriber A desires to talk with subscriber B, he lifts his telephone receiver from the switch-hook, in the usual manner, and thereby closes the circuit of battery Q through winding h of impedance coil I, conductor e , limb a of the telephone line, substation A, limb b of the line, conductor f , lamp g , and winding i of impedance coil I, which causes lamp g to light and thereby convey to the operator the signal for connection. The operator thereupon inserts answering plug E into a spring jack D, or any suitable connecting means, of line A, which 30 closes the circuit of battery Q through winding h of impedance coil I, conductor e , jack spring c , tip strand a_2 , supervisory lamp c_2 , winding d_2 of impedance coil N, sleeve strand b_2 , jack spring d , conductor f , lamp g , and winding i of impedance coil I; and through winding h of impedance coil I, conductor e , jack spring c , tip strand a_2 , lamp c_2 , impedance coil N, impedance coil O, and conductor y_2 . It will now be observed that 40 the path including jack spring c , tip strand a_2 , lamp c_2 , impedance coil N, sleeve strand b_2 , and jack spring d , is shunted by the path including limb a of the telephone line, substation A, and limb b of the line; and that 45 the path including conductor f , line lamp g , and winding i of impedance coil I, is shunted by the path including winding h_2 of impedance coil O, and conductor y_2 . In other words, the supervisory signal c_2 and impedance coil N are shunted by the line and substation apparatus belonging to subscriber A, and the line signal g and winding i of impedance coil I are shunted by impedance coil O. The resistance of the 55 supervisory signal c_2 and impedance coil N, is high, as compared with the resistance of the line and substation apparatus of subscriber A, and therefore the supervisory signaling device c_2 now gets insufficient current to 60 cause it to display a signal, as the line of

subscriber A takes the greater part of the current flowing over the combined paths of the line and the supervisory signal, as described, thus shunting the supervisory signal c_2 out. The resistance of the line signal g and winding i of impedance coil I, belonging to line A, is high, as compared with the resistance of impedance coil O, and therefore the line signaling device g now gets insufficient current to cause it to display a signal, as the impedance coil O takes the greater part of the current flowing over the combined paths of the line signal and impedance O, as described, thus shunting the line signal g out. The operator then depresses her listening key G, thereby causing springs j_2 and p_2 to disengage contacts k_2 and o_2 , respectively, and engage contacts i_2 and q_2 , respectively, which bridges her telephone set across the plug-cord talking circuit in a manner well understood.

25 After learning that subscriber B is the subscriber called for, and after testing the line B in any suitable manner and finding same to be not in use, the operator then inserts the calling plug F into a spring jack D of line B and then depresses the ringing key H, thereby causing springs m_2 and s_2 to disengage contacts n_2 and r_2 , respectively, and to engage contacts l_2 and t_2 , respectively, which signals subscriber B in a manner well understood. (In depressing the ringing key H, the operator also restores the listening key G to its normal position.) When subscriber B responds and lifts his 30 telephone receiver from the switch-hook, the subscribers A and B are connected for conversation with each other.

35 During the operation of calling subscriber B, a small amount of the calling current may pass through conductor e , impedance coil K, battery Q, conductor j , lamp g , and conductor f , but as the impedance of winding h of impedance coil K, and the resistance of lamp g , are preferably high, this current will be inappreciable. When line B is thus connected for conversation over same, the path including jack spring c , tip strand a_2 , spring m_2 , contact n_2 , spring j_2 , contact k_2 , supervisory lamp g_2 , spring p_2 , contact o_2 , contact r_2 , spring s_2 , sleeve strand v_2 , and jack spring d , is shunted by the path including limb a of the telephone line, substation B, and limb b of the line; and the path including conductor f of line B, and line-signal lamp g , is shunted by the path including conductor w_2 , impedance coil P, and conductor z_2 . In other words, the supervisory signal g_2 is shunted by the line and substation apparatus of subscriber B, and the line signal g of line B is shunted by the impedance coil P. The resistance of the supervisory signaling device g_2 is high, as compared with the resistance of the line and substation apparatus of subscriber B, 40 and 45 50 55 60 65 70 75 80 85 90 95 100 105 110 115 120 125 130

and therefore it now gets insufficient current from battery Q to cause it to display a signal, as the line B takes the greater part of the current flowing over the combined 5 paths of the line and the supervisory signal, as described, thus shunting the supervisory signal out. This supervisory lamp g_2 preferably has a very high resistance, say from 750 ohms to 1200 ohms, and requires a very 10 small current, say from .05 of an ampere to .04 of an ampere, to light it to candle power. The resistance of the line signaling device g of line B, is high, as compared with the resistance of impedance coil P, and therefore 15 fore it now gets insufficient current from battery Q to cause it to display a signal, as the impedance coil P takes the greater part of the current flowing over the combined paths of the line signal and impedance coil 20 P, as described, thus shunting the line signal out.

When the conversation is completed and subscriber A hangs his telephone receiver upon the switch-hook, he breaks the circuit 25 over his telephone line in a manner well understood, and thereby takes the shunt away from the supervisory lamp c_2 and allows it to light, thus conveying to the operator the signal for disconnection. The 30 supervisory lamp c_2 now lights over the path including winding h of impedance coil I, conductor e , jack spring c , tip strand a_2 , lamp c_2 , impedance coil N, impedance coil O, and conductor y_2 . The path including 35 sleeve strand b_2 , jack spring d , conductor f , lamp g , and winding i of impedance coil I, is now shunted by impedance coil O and conductor y_2 , and hence the line signal g remains extinguished.

40 When subscriber B hangs his receiver upon its switch-hook, he preferably breaks the circuit over his telephone line and thereby takes the shunt away from the supervisory lamp g_2 and allows it to light, thus 45 conveying to the operator his signal for disconnection. The supervisory lamp g_2 now lights over the path including winding h of impedance coil K, conductor e , jack spring c , tip strand u_2 , spring m_2 , contact 50 n_2 , spring j_2 , contact k_2 , lamp g_2 , conductor w_2 , impedance coil P, and conductors z_2 and j . The path including spring p_2 , contact o_2 , contact r_2 , spring s_2 , sleeve strand v_2 , jack contact d of line B, conductor f , and line- 55 signal lamp g , is now shunted by conductor w_2 , impedance coil P, and conductor z_2 , and hence the line signal g belonging to line B remains extinguished.

It is evident that if either subscriber A 60 or B should again remove his telephone receiver from the switch-hook while connection is still made with his line, he would cause his supervisory signal to be extinguished. Therefore by operating his switch- 65 hook, (alternately closing and opening the

circuit of the line) either subscriber may signal the operator for a second connection, while connection is still made with his line, through the agency of his supervisory 70 signal.

When the operator receives both disconnect signals from subscriber A and B, respectively, she withdraws the connecting plugs E and F from their respective spring jacks, thereby breaking the circuits of battery Q from the supervisory signals c_2 and g_2 and restoring both lines and all circuits and apparatus to their normal condition. 75

It is evident that subscriber B may be the calling subscriber and subscriber A the called subscriber, in which case answering plug E would be connected with line B, and calling plug F with line A, and the operations with lines A and B being interchanged. 80

For the supervisory signal lamps I preferably use lamps requiring a small current to light them, say from .05 of an ampere to .04 of an ampere, and consequently of a high resistance in relation to their voltage. 85

The double-wound impedance coil I, which I preferably use in line A, is a distinct improvement over two separate impedance coils, in that the windings of the double-wound coil exert a mutual induction 90 on each other, in addition to the self-inductions of the single-wound coils, the said mutual induction tending to greatly reduce the flow of alternating currents from one limb of the telephone line through the central source of electricity and the windings of the double-wound coil I back to the other limb of the line, and hence resisting the flow of talking currents through the said windings. The double-wound coil 95 gives the mutual induction and self-induction whereas the single-wound coils give only the self-induction. 100

In Fig. 2, I have shown the supervisory signals c_3 and g_3 connected in circuit with 110 their respective windings d_3 and f_3 of a repeating coil L, signal c_3 and winding d_3 being also connected in circuit with tip strand a_2 and sleeve strand b_2 of answering plug E, and signal g_3 and winding f_3 being normally 115 connected through listening key G and ringing key H, in circuit with tip strand u_2 and sleeve strand v_2 of calling plug F. With this arrangement the condensers e_2 and f_2 of Fig. 1 are done away with and the central source of current is preferably connected to one strand of each connecting cord through conductor r and a single impedance coil M, preferably as shown. The supervisory signals c_3 and g_3 operate similarly 125 to supervisory signals c_2 and g_2 of Fig. 1. The talking currents traverse the supervisory signals c_3 and g_3 , being repeated from one telephone line to the other through the repeating coil L, in a manner well un- 130

derstood. The talking currents traversing line A, answering cord E, supervisory lamp e_3 and winding d_3 of repeating coil L, are repeated through winding f_3 of repeating 5 coil L, supervisory lamp g_3 , calling cord F, and line B, or vice versa, if connection is made with lines A and B. In depressing the listening key the operator preferably connects her telephone set in circuit with 10 contact i_2 , spring j_2 , condenser e_3 , lamp g_3 , winding f_3 of repeating coil L, spring p_2 , and contact q_2 , springs j_2 and p_2 at the same time disengaging contacts h_2 and o_2 , respectively. When the key G is thus depressed, 15 the talking currents from the operator's telephone are repeated through the repeating coil L to the line which is connected with answering plug E, or vice versa.

In speaking of signaling devices, or the 20 like, I contemplate any suitable electrically-operable device, as, for example, an annunciator having a visual signal.

It is also intended that a relay controlling 25 a signal shall come within the scope of the appended claims.

While I have illustrated my invention in connection with particular types of spring jacks, connecting plugs, listening key, ringing key, lamps, repeating coil, impedance 30 coils, subscriber's instrument, source of electric current, etc., it is to be understood that different types of these several pieces of apparatus may be used in this invention with good results.

35 While this invention is illustrated in connection with multiple switchboard systems, it will be understood that its features are also applicable to telephone systems of the single, transfer, or divided-board types.

40 I do not wish to limit this invention to all of the particular details herein set forth, as various modifications thereof may be made or utilized without departing from the scope of the appended claims.

45 Having thus described my invention, what I claim as new is—

1. The combination with a telephone line and connection terminals therefor, of a signaling device associated with the line, a 50 plug-cord circuit adapted to be connected with the connection terminals, a source of electricity associated with the line, a resistance through which the said source is associated with a main strand of the cord circuit, 55 a lamp in series with a resistance, bridged across the main strands of the cord circuit, and means whereby, when connection is made with the line, the circuit of the said source is closed through a main connection 60 terminal of the line, a main contact of the connecting plug, a main strand of the connecting cord, the said lamp with its resistance, and the resistance through which the said source is associated with the cord cir-

cuit, thus lighting the said lamp, substantially as described.

2. A telephone line having a connection terminal, a central source of electricity associated with the line, connecting means for the line comprising a pair of conductors to be included in the talking circuit, signal-initiating means in a series circuit with a portion of the said pair of conductors, means whereby the said signal-initiating means is supplied with electricity from the said source from the telephone line through the connection terminal, for actuating the signal-initiating means, when connection is made with the line, and means whereby the telephone line shunts the signal-initiating means, relatively to the said source, when connection is made with the line and the latter is in use, to render the said signal-initiating means inactive.

3. A telephone system having a plurality 85 of lines extending to a central station and supplied by a common source of electricity, in combination with a connecting circuit for the lines having a pair of conductors to be included in the talking circuit, a condenser in each conductor of the pair, a signal-initiating device connected across the said pair of conductors on one side of the said condensers, means whereby the signal-initiating device is supplied with electricity 90 from a telephone line through a portion of one of the said pair of conductors when connection is made with the line, and means whereby the telephone line shunts the signal-initiating device to render same inactive 95 when connection is made with the line and the latter is in use.

4. A telephone line extending from a substation to a source of electricity at a central station, a connecting circuit for the line, a lamp bridged across the talking strands of the connecting circuit, means whereby connection with the line supplies the said lamp with current to light same, over a portion of the line extending to the said source, when the line is not in use, the said connection causing the line extending to the substation to shunt the said lamp out when the line is in use.

5. An electrical transmitting line, a connecting circuit therefor having a conductive path comprising portions of the main strands of the connecting circuit and a signal-initiating device, a central source of electricity connected with one of the said main strands exclusive of the said path, and means whereby the said signal-initiating device is connected with at least one pole of the said source over a line connection when connection is made with the line, for energizing the said device.

6. An electrical transmitting line, a connecting circuit therefor having conductors

for transmitting the electrical transmission currents of the line to another line, a signal-initiating device bridged across the said conductors, and a central source of electricity having connections exterior of the

5 tricity having connections exterior of the said bridge for supplying the said device with energizing current, at least one of the said connections being through a line connection when connection is made with the

10 line.

7. A telephone line, a connecting circuit therefor having conductors adapted to be included in the talking circuit, a signal lamp bridged across the said conductors, a source

15 of electricity exterior of the said lamp bridge, and means whereby the said lamp is supplied with electricity from the said source over a line connection, for lighting the said lamp, when connection is made with

20 the line.

8. A telephone line, a connecting circuit therefor having a conductive path comprising portions of the main strands of the connecting circuit and a signal-lamp, a source

25 of electricity exterior of the said conductive path, and means whereby the said lamp is supplied with electricity from the said source over a line connection, for lighting the said lamp, when connection is made with

30 the line.

9. An electrical transmitting line, a connecting circuit therefor having conductors for transmitting the electrical transmission currents of the line to another line, a signal-

35 initiating-device-bridge across the said conductors, a central source of electricity for supplying current through the said bridge to energize the said device, and suitable circuit connections whereby the said line when

40 in use forms a shunt-circuit around the said bridge to render the said device inactive, the said shunt-circuit including no part of the said bridge.

10. The combination with a telephone line

45 of a connecting circuit therefor having a pair of talking strands, a signal-initiating-device-bridge across the said talking strands, a central source of electricity for supplying current through the said bridge to actuate the said device, and suitable circuit connections whereby the said line when in use forms a shunt-circuit around the said bridge, in relation to the said source, to render the said device inactive, the said

50 shunt-circuit including no part of the said bridge.

11. The combination with a telephone line

60 and a connecting circuit therefor having a pair of talking strands, of an impedance bridge across the said talking strands, said bridge containing a signal-initiating device, a central source of electricity for supplying current through the said bridge to actuate the said device, and suitable circuit connec-

tions whereby the said line when in use

65 forms a shunt-circuit around the said bridge, in relation to the said source, to render the said device inactive, the said shunt circuit including no part of the said bridge.

12. A telephone line, a connecting circuit

70 therefor having conductors adapted to be included in the talking circuit, a signal-lamp bridge across the said conductors, a source of current for lighting the said lamp, and suitable circuit connections whereby the

75 said line when in use forms a shunt-circuit around the said lamp bridge to render the said lamp inactive, the said shunt-circuit including no part of the said bridge.

13. A telephone line, a connecting circuit

80 therefor having talking limbs adapted to be connected with the line, a signal lamp constructed to carry a maximum current not greater than approximately five-onehundredths of an ampere and bridged across the

85 said talking limbs, a source of current having connections exterior of said bridge for lighting the said lamp, and suitable circuit connections whereby the said line when in use forms a shunt-circuit around the said

90 lamp to render same incapable of displaying a signal, the said lamp permitting a line of exceptionally high resistance to shunt it as specified.

14. In a telephone system having lines

95 extending to a central station, a metallic connecting circuit for the lines terminating in a pair of connecting devices, a condenser in each limb of the metallic connecting circuit, a signal-initiating device bridged

100 across the said metallic connecting circuit, and a central source of electricity having connections exterior of the said bridge for supplying the said device with energizing current, at least one of the said connections

105 being through a line connection when connection is made with a line.

15. In a telephone system having lines

110 extending to a central station, a metallic connecting circuit for the lines terminating in a pair of connecting devices, a condenser in each limb of the metallic connecting circuit, a signal-initiating-device bridge across the said metallic connecting circuit, means for energizing the said signal-initiating device as desired, and suitable circuit connections whereby the said signal-initiating device is shunted and thereby rendered inactive, by a line circuit when connection is made with a line, the said line-circuit shunt

115 forming no part of the said bridge.

16. A telephone line, a connecting circuit

125 for the line having a pair of conductors to be included in the talking circuit, a signal-initiating device bridged across the said pair of conductors, and a central source of electricity having connections exterior of the said bridge for supplying the said device

with energizing current, at least one of the said connections being through a line connection when connection is made with the line.

5 17. An electrical transmitting line, a connecting circuit therefor having a pair of conductors to be included in the main circuit, signal-initiating means bridged across the said pair of conductors, a central source 10 of electricity having connections exterior of the said bridge for supplying current through the said bridge to energize the said device.

15 the said source over a line connection when connection is made with the line.

18. The combination with a telephone line and a connecting circuit therefor having a pair of talking conductors extending from the line to the connecting circuit when the latter is connected with the line, of a permanently continuous conductive path comprising portions of the said talking conductors and a supervisory signal-initiating de-

25 vice, and a central source of electricity having connections with the said talking conductors whereby the said device is supplied with energizing current when connection is made with the line, the said connections 30 from the said source to the said talking conductors being exclusive of the said conductive path and at least one of them being made with the line portion of one of the said talking conductors.

35 19. The combination with a telephone line and a connecting circuit therefor having a pair of talking conductors extending from the line to the connecting circuit when the latter is connected with the line, of a permanently continuous conductive path comprising portions of the said talking conductors and a supervisory signal-initiating de- 40 vice, and a central source of electricity having connections with the said talking conductors whereby the said device is supplied with energizing current when connection is made with the line, the said connections from 45 the said source to the said talking conductors being exclusive of the said conductive path.

50 20. The combination with electrical transmitting lines, of a connecting circuit therefor having a pair of conductors terminating in a pair of connecting devices, a signal-initiating device bridged across the said pair of conductors, and a central source of electricity having connections exterior of the said bridge for supplying current through the said bridge to energize the said signal-initiating device.

55 21. A telephone line, a connecting circuit for the line having a pair of conductors to be included in the talking circuit, a signal-initiating device bridged across the said pair

of conductors, and a central source of electricity having connections exterior of the said bridge for supplying current through the said bridge to energize the said device.

60 22. The combination with an electrical transmitting line; of a connecting circuit 70 therefor having a pair of conductors to be included in the main circuit, signal-initiating means bridged across the said pair of conductors, and a central source of electricity 75 having connections exterior of the said bridge for supplying electricity through the said bridge to energize the said signal-initiating means.

23. A telephone line, a connecting circuit therefor having conductors adapted to be 80 included in the talking circuit, a signal lamp bridged across the said conductors, and a central source of electricity having connections exterior of the said bridge for supplying the said lamp with energizing current, 85 at least one of the said connections being through a line connection when connection is made with the line.

24. In combination, a telephone line, a connecting circuit therefor having a signal-initiating device associated therewith, a central source of electricity, means for energizing the said device from the said source while the said device is free from a shunt therearound, and means whereby the line 90 when in use forms a shunt-circuit around the said device, relatively to the said source, to render the said device inactive.

25. In combination, an electrical transmitting line, a signal lamp, a source of electricity, means for energizing the said lamp from the said source while the said lamp is free from a shunt therearound, and means whereby the line when in use forms a shunt-circuit around the said lamp to render the 95 latter inactive.

26. The combination with an electrical transmitting line and a connecting circuit therefor, of a signal-initiating device associated with the connecting circuit, a central 100 source of electricity, means for energizing the said device from the said source while the said device is free from a shunt therearound, and means whereby the line when in use forms a shunt-circuit around the said device, relatively to the said source, to render the 105 said device inactive.

27. The combination with a telephone line and a connecting circuit therefor, of a signal lamp associated with the connecting circuit, a source of electricity, means for lighting the said lamp from the said source while the said lamp is free from a shunt therearound, and means whereby the line when in use forms a shunt-circuit around the said lamp to render same inactive.

120 28. The combination with a telephone line and a connecting circuit therefor, of a sig-

nal lamp constructed to carry a maximum current not greater than approximately five-onehundredths of an ampere and associated with the connecting circuit, a source of electricity, means for lighting the said lamp from the said source while the said lamp is free from a shunt therearound, and means whereby the line when in use forms a shunt-circuit around the said lamp to render same incapable of displaying a signal, the said lamp permitting a line of exceptionally high resistance to shunt it as specified.

29. The combination with a telephone line, of a signal lamp constructed to carry a maximum current not greater than approximately five-onehundredths of an ampere, a source of electricity, means for lighting the said lamp from the said source while the said lamp is free from a shunt therearound, and means whereby the line when in use forms a shunt-circuit around the said lamp to render same incapable of displaying a signal, the said lamp permitting a line of exceptionally high resistance to shunt it as specified.

30. The combination with a telephone line and a connecting circuit therefor, of an impedance-bridge across the main strands of the connecting circuit, a signal-initiating device, and a central source of electricity having connections exterior of the said bridge whereby a current may be sent from a line connection through the said impedance-bridge and the said signal-initiating device to effect the actuation of the latter.

31. The combination with a telephone line and a connecting circuit therefor having a pair of talking conductors extending from the line to the connecting circuit when the latter is connected with the line, of a conductive path comprising portions of the said talking conductors and a supervisory signal-initiating device, a central source of electricity having connections with the said talking conductors whereby the said device is supplied with energizing current when connection is made with the line, the said connections from the said source to the said talking conductors being exclusive of the said conductive path, and means whereby the line when in use forms a shunt-circuit around the said device to render same inactive.

32. An electrical transmitting line, a connecting circuit therefor having a conductive path comprising portions of the main strands of the connecting circuit and a signal-initiating device, a central source of electricity connected with one of the said main strands exclusive of the said path, means whereby the said signal-initiating device is connected with at least one pole of the said source over a line connection when connection is made with the line, for

energizing the said device, and means whereby the line when in use forms a shunt-circuit around the said device to render same inactive.

33. An electrical transmitting line, a connecting circuit therefor having conductors for transmitting the electrical transmission currents of the line to another line, a signal-initiating device bridged across the said conductors, a central source of electricity having connections exterior of the said bridge for supplying the said device with energizing current, at least one of the said connections being through a line connection when connection is made with the line, and means whereby the line when in use forms a shunt-circuit around the said device to render same inactive.

34. In a telephone system having lines extending from a central station to substations, a connecting circuit for the lines at the central station, a supervisory signal-initiating device bridged across the main strands of the connecting circuit, and a central source of electricity for initially energizing the said device, the said source having connections exterior of the said bridge for supplying the said energizing current.

35. In a telephone system having lines extending from a central station to substations, a connecting circuit for the lines at the central station, a supervisory signal-initiating device in a permanently continuous circuit with portions of the main strands of the connecting circuit, and a central source of electricity for initially energizing the said device, the said source having connections exterior of the said permanently continuous circuit for supplying the said energizing current.

36. In a telephone system having lines extending from a central station to substations, a connecting circuit for the lines at the central station, a supervisory signal-initiating device adapted to be bridged across the main conductors of the circuit when connection is made with a line, and a central source of electricity for initially energizing the said device, the said source having connections exterior of the said bridge for supplying the said energizing current.

37. In an electrical system having lines extending from a central station to substations, a connecting circuit for the lines at the central station, an electrically-operable device bridged across the main strands of the connecting circuit, and a central source of electricity for initially energizing the said device, the said source having connections exterior of the said bridge for supplying the said energizing current.

38. In an electrical system having lines extending from a central station to sub-

stations, a connecting circuit for the lines at the central station, an electrically-operable device in a permanently continuous circuit with portions of the main strands of the connecting circuit, and a central source of electricity for initially energizing the said device, the said source having connections exterior of the said permanently continuous circuit for supplying the said energizing current.

39. In an electrical system having lines extending from a central station to substations, a connecting circuit for the lines at the central station, an electrically-operable device adapted to be bridged across the main conductors of the circuit when connection is made with a line, and a central source of electricity for initially energizing the said device, the said source having connections exterior of the said bridge for supplying the said energizing current.

40. In a telephone system having lines extending from a central station to substations, a connecting circuit for the lines at the central station, a supervisory signal-initiating device bridged across the main strands of the connecting circuit, and a central source of electricity for initially energizing the said device, the said source having connections exterior of the said bridge for supplying the said energizing current, the said device being shunted by a line circuit and thereby rendered inactive when connection is made with a line in use.

35 41. In a telephone system having lines extending from a central station to substations, a connecting circuit for the lines at the central station, a supervisory signal-initiating device in a permanently continuous circuit with portions of the main strands of the connecting circuit, and a central source of electricity for initially energizing the said device, the said source having connections exterior of the said permanently continuous circuit for supplying the said energizing current, the said device being shunted by a line circuit and thereby rendered inactive when connection is made with a line in use.

40 42. In a telephone system having lines extending from a central station to substations, a connecting circuit for the lines at the central station, a supervisory signal-initiating device adapted to be bridged across the main conductors of the circuit when connection is made with a line, and a central source of electricity for initially energizing the said device, the said source having connections exterior of the said bridge for supplying the said energizing current, the said device being shunted by a line circuit and thereby rendered inactive when connection is made with a line in use.

43. In an electrical system having lines extending from a central station to substations, a connecting circuit for the lines at the central station, an electrically-operable device bridged across the main strands of the connecting circuit, and a central source of electricity for initially energizing the said device, the said source having connections exterior of the said bridge for supplying the said energizing current, the said device being shunted by a line circuit and thereby rendered inactive when connection is made with a line in use.

tions, a connecting circuit for the lines at the central station, an electrically-operable device bridged across the main strands of the connecting circuit, and a central source of electricity for initially energizing the said device, the said source having connections exterior of the said bridge for supplying the said energizing current, the said device being shunted by a line circuit and thereby rendered inactive when connection is made with a line in use.

44. In an electrical system having lines extending from a central station to substations, a connecting circuit for the lines at the central station, an electrically-operable device in a permanently continuous circuit with portions of the main strands of the connecting circuit, and a central source of electricity for initially energizing the said device, the said source having connections exterior of the said permanently continuous circuit for supplying the said energizing current, the said device being shunted by a line circuit and thereby rendered inactive when connection is made with a line in use.

45. In an electrical system having lines extending from a central station to substations, a connecting circuit for the lines at the central station, an electrically-operable device adapted to be bridged across the main conductors of the circuit when connection is made with a line, and a central source of electricity for initially energizing the said device, the said source having connections exterior of the said bridge for supplying the said energizing current, the said device being shunted by a line circuit and thereby rendered inactive when connection is made with a line in use.

46. The combination with electrical transmitting lines, of a connecting circuit therefor containing a signal-initiating device, a source of electricity, means for energizing the said device from the said source while the said device is free from a shunt there-around, and means whereby the circuit of a line forms a shunt around the said device to render same inactive, when connection is made with the line.

47. The combination with a telephone line, of a signal lamp constructed to carry a maximum current not greater than approximately five-onehundredths of an ampere, a source of electricity for supplying current to light the said lamp, and means whereby the line when in use forms a shunt around the said lamp to render same incapable of displaying a signal, the said lamp permitting a line of either low or exceptionally high resistance to shunt it as specified.

48. The combination with a telephone line and a connecting circuit therefor, of an impedance-bridge across the main strands of the connecting circuit, a signal-initiating

device, and a central source of electricity having connections exterior of the said bridge whereby a current may be sent through the said impedance-bridge and the said signal-initiating device to effect the actuation of the latter.

5 As inventor of the foregoing, I hereunto

subscribe my name in the presence of two subscribing witnesses, this 1st day of August, A. D., 1904.

FREDERICK R. PARKER.

Witnesses:

R. G. PARKER,
Wm. F. VIOLETT.
